UNITED STATES PATENT OFFICE.

FRED W. TOBEY, OF GRAND RAPIDS, MICHIGAN, ASSIGNOR TO ALFRED J. BROWN SEED CO., A CORPORATION OF MICHIGAN.

DESIGN FOR A CABINET.

50,923.

Specification for Design. Patented June 12, 1917.

Application filed April 28, 1917. Serial No. 165,283. Term of patent 7 years.

To all whom it may concern:

Be it known that I, FRED W. TOBEY, a citizen of the United States, residing at Grand Rapids, in the county of Kent and State of Michigan, have invented a new, original, and ornamental Design for Cabinets, of which the following is a specification, reference being had to the accompanying drawing, forming part thereof.

The figure is a view in perspective of a cabinet, showing my new design.

I claim:

The ornamental design for a cabinet as shown.

FRED W. TOBEY.

Witnesses:

CYRUS W. RICE,
JULIA C. OLSEN.
